UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

AMPLIFIER TUBE CONTROL

Application filed March 30, 1929. Serial No. 351,405.

My present invention relates to amplifier tubes, and, more particularly, to a transmitter amplifier circuit employing a portion of its input to control plate current consumption.

5 In operating a transmitter, the amplifier tubes should, for ideal performance, be subjected to maximum plate heating only when the radio frequency input is at a maximum. 10 By employing an expedient which involves the utilization of a portion of the input radio frequency current, I achieve satisfactory performance of the amplifier tubes.

It is one of the main objects of the present invention to provide an amplifier tube operating in such a manner that the biasing potential on its grid is reduced when the input is of a large amplitude, and the grid bias is at a maximum when the input to the tube 20 is small, thus resulting in control of the plate current consumption.

Another important object of the invention is to provide an amplifier tube in a transmitting circuit, which tube is biased highly negative when the tube is not subjected to radio frequency impulses, and additional means to supply a variable potential counter to the grid biasing potential in accordance with input variations.

30 Still another object of the invention is to provide an amplifier tube circuit which includes in the grid circuit of the tube means, responsive to variations in the radio frequency input, to supply a filtered continuous current to the said grid circuit, the potential of the current being counter to the biasing potential of the grid whereby the average current flowing through the plate circuit of the tube increases with the input amplitude.

40 The novel features which I believe to be characteristic of my invention are set forth in particularity in the appended claim, the invention itself, however, as to both its organization and method of operation, will best be understood by reference to the following description taken in connection with the drawing in which I have indicated diagrammatically one circuit organization whereby my invention may be carried into effect.

In the drawing, Fig. 1 is a circuit diagram embodying my invention,

Fig. 2 is a graphic representation of the operating characteristic of the tube shown in Fig. 1.

55 Referring to the accompanying drawing, there is shown an amplifier tube circuit in Fig. 1, the circuit showing only the connections to and from the amplifier tube for the sake of simplicity. The input circuit A is coupled, as shown, to the grid-filament circuit of the tube A. T., the tube being any conventional transmitter amplifier tube, the plate, or output, circuit of which is energized by as source of current B. The grid of the tube is biased by a source of current C, and includes, in circuit with the biasing source, a condenser C₂ shunted by a resistance or "leak" R.

60 The input circuit A is coupled to the grid circuit of the tube at two points D, E, the coupling E being effected between the condenser C₂ and the grid of the tube, while the coupling D is made to a rectifier circuit shunted across the resistance R. The secondary coil of the coupling D has associated therewith a variable slider 3 at one end thereof, and is connected at the other end to any conventional rectifier device.

65 The output from the slider 3 and rectifier is passed through a filtering section, the latter comprising choke coils L₁, L₂, each of which coils is in series with the slider 3 and the rectifier respectively, a condenser C₁ being connected across the coil, the purpose of the filtering section being to smooth out the pulsating direct current derived from the rectifier.

70 The operation of the circuit will appear obvious from the arrangement shown, it being understood that by properly proportioning the couplings D, E, the leak resistance R, and the condensers C₁, C₂, the amplifier grid can be kept just more negative than the value of the radio frequency input at A when large inputs occur, but very much negative when the input is small. The purpose of the rectifier is to vary the operating point of the grid 75 80 85 90 95 100

in accordance with the change of input to the tube.

For example, in Fig. 2, I have shown what would happen on the characteristic curve of the tube A. T. when the input at A increases from one value to another, it being observed that when the increase occurs the operating point of the grid is moved from point 1 to point 2 on the characteristic curve, thus increasing the plate current flowing through the plate circuit of the tube only when the radio frequency input increases.

The grid of the tube A. T. is normally biased highly negative by the source C. The rectifier circuit is so arranged across the resistance R, that, when a radio frequency current flows through the input A, a portion of the input is imposed upon the rectifier circuit through the coupling D while the remainder of the input is imposed directly upon the coupling E. The slider 3 being positioned for optimum operation, the rectifier will pass a pulsating direct current through the filter section, the pulsating current being smoothed out in flowing therethrough, and the current being finally impressed upon the grid circuit of the tube so as to oppose the potential of the biasing source C.

It will be obvious then that when the input current increases, the total biasing potential will decrease and the plate current flowing through the output circuit of the tube therefor increase. Conversely, a decrease in the input current will result in a decrease in the rectified current flowing counter to the current from the source C and the plate current will correspondingly drop. It will thus be seen that I have devised a method and means for controlling the consumption of plate current in an amplifier tube, used either in a transmitting or even in a receiving circuit. It is to be observed that this method not only conserves power, but also avoids the necessity for running the plate of the tube at high temperatures during periods when signals are not being applied to its grid. Thus, the tube may be arranged to utilize momentary over-loading during instants of great signal input without overheating the plate.

While I have indicated and described only one system for carrying my invention into effect, it will be apparent to one skilled in the art that my invention is by no means limited to the particular organization shown and described, but that many modifications in the circuit arrangement as well as in the apparatus employed, may be made without departing from the scope of my invention as set forth in the appended claim.

What I claim is:

An arrangement for reducing current losses in the anode circuit of a power amplifier tube comprising a source of signal voltage, a source of negative potential disposed in the grid cir-

cuit of the tube, said second source being of sufficient magnitude to reduce the current flowing in the said anode circuit to substantially zero in the absence of signal voltage in the said grid circuit, and a third source of potential disposed in said grid circuit, said third source being derived from said signal voltage source and arranged in opposition to said second source in such a manner that the operating grid potential of the tube is of suitable value for efficient amplification only while signal voltage is impressed on the grid circuit of said tube.
